UNITED STATES PATENT OFFICE.

JAMES FRANK HILYARD, OF RANCOCAS, NEW JERSEY.

DESIGN FOR A SPOON.

SPECIFICATION forming part of Design No. 22,197, dated February 7, 1893.

Application filed September 21, 1892. Serial No. 446,479. Term of patent 14 years.

To all whom it may concern:

Be it known that I, JAMES FRANK HILYARD, a citizen of the United States, residing at Rancocas, in the county of Burlington and State 5 of New Jersey, have invented and produced a new and original Design for a Spoon, of which the following is a specification, reference being had therein to the accompanying drawings, forming part thereof, in which—

Figure 1 represents a perspective view of a spoon embodying my design. Fig. 2 represents a top or plan view thereof.

Similar letters of reference indicate corresponding parts in the two figures. 15 The leading feature of my design for a spoon is a bridge above the marginal line of the bowl with openings on opposite sides of said bridge. The walls of the bridge are serpentine, the central portion of one wall curving

inwardly, and that of the other wall bulging 20 outwardly.

In the drawings: A designates a bridge over the bowl C of the spoon.

B, B, designate openings between the side walls of the bridge and top or marginal line D 25 of the bowl, said walls being curved or serpentine. The central portion E of one wall curves inwardly. The central portion F of the other wall bulges outwardly. The openings B are above the top or marginal line of the bowl. 30

I claim,—

The design for a spoon substantially as herein shown and described.

J. FRANK HILYARD.
